(57) **CLAIM**

The ornamental design for a vacuum excavator hose handle, as shown and described.

DESCRIPTION

FIG. 1 is a front view of the vacuum excavator hose handle of my invention. Two such handles, identical in design, are shown on either side of an unclaimed hose component.

FIG. 2 is a left side view thereof.

FIG. 3 is a back view thereof.

FIG. 4 is a right side view thereof.

FIG. 5 is a top view thereof.

FIG. 6 is a bottom view thereof.

FIG. 7 is a top front left perspective view thereof.

FIG. 8 is a bottom front left perspective view thereof.

FIG. 9 is a front view of the vacuum excavator hose handle of FIGS. 1-8, with upstream and downstream hoses shown for providing environmental context to the claimed design.

FIG. 10 is a front view of a single vacuum excavator hose handle.

The broken line elements are included for the purposes of illustrating portions of the vacuum excavator hose handle and surrounding environmental structure and form no part of the claimed design.
